(57) **CLAIM**

The ornamental design for a closure, as shown.

DESCRIPTION

FIG. 1 is a top front perspective view of a first embodiment of the closure;

FIG. 2 is a rear elevational view of the closure of FIG. 1, with the left and right side elevational views being identical to the rear elevational view;

FIG. 3 is a top plan view of the closure of FIG. 1;

FIG. 4 is a top front perspective view of a second embodiment of the closure;

FIG. 5 is a rear elevational view of the closure of FIG. 4, with the left and right side elevational views being identical to the rear elevational view; and,

FIG. 6 is a top plan view of the closure of FIG. 4.
